UNITED STATES PATENT OFFICE.

HERBERT PAYNE FISHER, OF LOS ANGELES, CALIFORNIA.

AUTOMATIC WATER-HEATER.

1,312,724.

Specification of Letters Patent. Patented Aug. 12, 1919.

Application filed January 8, 1917, Serial No. 141,244. Renewed February 11, 1919. Serial No. 276,422.

To all whom it may concern:

Be it known that I, HERBERT PAYNE FISHER, a citizen of the United States, residing at Los Angeles, in the county of Los Angeles and State of California, have invented certain new and useful Improvements in Automatic Water-Heaters; and I do declare the following to be a full, clear, and exact description of the invention, such as will enable others skilled in the art to which it appertains to make and use the same.

This invention relates to automatic instantaneous water heaters and to the mechanism for controlling the supply of gas used for heating the water.

One object of the invention is to provide a simple and efficient heater of this character which is so constructed that the coil will not scale or lime up, all of the deposits being broken up during its use.

Another object is to provide a thermostatic regulating valve having an extended range of action.

Another object is to provide a valve of this character which operates freely under all conditions; opens quickly when the water in the heaters becomes cold, allowing the water to flow immediately through the coil, and closes immediately the water reaches the required temperature.

Still another object is to provide a valve of this character so constructed as to render all parts easily removable to facilitate repairs.

Another object is to provide for the adjustment of the valve operating mechanism so that the valves will cut off the fuel supply when the water reaches a predetermined temperature.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a vertical section with the parts in side elevation of a heater constructed in accordance with this invention; Fig. 2 is a horizontal section taken on the line 2—2 of Fig. 1;

Fig. 3 is an enlarged detail longitudinal section through the valve casing and thermostat showing the connections between the valve and thermostat; 60

Fig. 4 is a vertical section taken on the line 4—4 of Fig. 3;

Fig. 5 is a detail plan view;

Fig. 6 is a transverse section taken on the line 6—6 of Fig. 3; and 65

Fig. 7 is a detail vertical section through sleeve 41.

In the embodiment illustrated, a boiler 1 is shown which may be of any type of receptacle from which water is drawn off for household or other purposes and which is preferably mounted within an insulated casing 1' which serves to retain the heat within the boiler. 70

This boiler has an outlet 2 at its top 75 through which the heated water is drawn and has a gravity outlet pipe 3 at its bottom which connects the boiler with a thermostatic casing 13 to be described.

A water leg or pipe 4 extends through the 80 bottom of the boiler to a point near its top and is designed for conveying hot water into the boiler and discharging it thereinto at the top ready to be drawn out through the outlet 2, it being well understood that owing 85 to the natural law of gravity, the hotter of two bodies of water ascends while a corresponding volume of cold water will fall.

The water leg 4 is connected below the 90 bottom of the boiler with a heater coil 5 by a curved pipe 6 which connects with a coupling 7 on pipe 4 and with another coupling 8 carried by the upper end of the coil 5 and which connects said coil with a pipe 9 leading to a radiator (not shown) or 95 other desired point.

This coil 5 is formed of metal tubing wound in truncated cone or pyramidal shape and is disposed in a chamber 10 below the boiler. A gas burner 11 is arranged below 100 said coil so that the heat and flame emanating therefrom passes up through the coil and strikes the bottom of the boiler which deflects it down against the outer face of the coil, the exhausted heat passing out 105 through a flue opening 12 formed in the side of the chamber 10.

A horizontally disposed thermostat casing 13 is supported below the burner 11 and is here shown cylindrical in form with a 110 coupling 14 at one end with which is connected the lower end of the coil 5. A cou-

pling 15 is secured to the other end of the casing, said coupling being what is termed a four-way coupling and having a screw threaded plug 16 in the outer end 5 which is arranged in longitudinal alinement with the casing, a thermostatic tube 17 being mounted in said casing and carried by said plug as is shown clearly in Fig. 3, the purpose of which will be presently described.

The gravity pipe 3 which leads from the bottom of the boiler 1 connects with the upper end of the coupling 15 and the opposed end of said coupling is designed to 15 be connected with a cold water supply pipe through which water for filling the system is designed to enter.

The thermostatic tube 17 is composed of brass or any suitable metal which readily 20 contracts and expands under the influences of heat and cold and which terminates within the casing 13 at a point spaced from its rear end a sufficient distance to permit said tube to expand under the action of hot water 25 flowing through the casing 13.

A bracket 18 is supported on the front end of the casing 13 and carries a valve casing 19 which is disposed in the gas line or main pipe of a gas system. This casing 19 30 may be of any suitable or desired conformation and is here shown cylindrical with an offset chamber 20 at one side thereof which carries a needle valve 21 which controls the supply of gas to a pilot light which is positioned adjacent the burner so that said 35 burner will light when the gas is turned on.

A bell crank lever 22 is fulcrumed on the bracket 18 and one arm 23 thereof is positioned in the path of a thermostat-actuated 40 rod 24 which is inclosed in the thermostat tube 17, said rod projecting through the outer end of the plug 16 and normally engaging the arm 23 of the lever 22 as is shown clearly in Fig. 3. This rod 24 is composed 45 of any suitable non-expansive and contractible material, being preferably composed of six parts ground flint, one part diatomaceous earth, and one part Portland cement, with enough water to make a thick paste. This 50 mixture is then formed into the desired shape and baked and shows less expansion when heated than either carbon or porcelain, hence adapting it especially for the use for which it is intended.

The other arm 23' of the bell crank 22 extends in a horizontal plane and is designed to be engaged by a roller 25 carried by a vertically movable rod 26 which is mounted to reciprocate in a sleeve 27 which depends 60 from the bottom of the valve casing 19. Secured within the casing 19 is a registering sleeve 28 provided with a laterally extending bifurcated lug 29 into which is designed to extend a finger 30 which depends from 65 the lower face of the disk valve 31 disposed

within the casing 19 and which is designed to seat on an annular flange 32 carried by the side walls of the casing between its upper and lower ends. This valve 31 has a knife-edged flange 33 extending laterally around 70 its lower face at the periphery thereof and which insures airtight engagement of the valve with its seat. When the finger 30 of said valve is engaged by the bifurcated lug 29, the valve is held against turning but is 75 permitted to move vertically within the casing, the finger 30 being sufficiently long to be engaged always with said lug no matter in what position the valve may be disposed.

The casing 19 is preferably closed by a 80 cap 34 having an annular exteriorly threaded flange 35 on its lower face spaced inwardly from its perimeter a distance equal to the thickness of the side walls of the casing, said threaded flange being designed for threaded 85 engagement with the inner faces of said side walls which are correspondingly threaded to receive it. This closure 34 has a central aperture 36 around which is formed an annular boss 37.

The valve 31 and its seat 32 forms a horizontal partition within the casing 19 and a gas inlet 38 communicates with the lower portion of the casing below the valve, while an outlet 39 which leads to the burner 11 95 communicates with the casing above said valve, said outlet 39 being connected with the burner by a suitable pipe 40. It will thus be seen that when the valve is seated in closed position the gas supply will be cut off 100 from said burner and the pilot light only supplied, and when the valve is opened the burner is put in communication with the gas main and gas is caused to flow to the burner which is ignited by the pilot in the usual 105 manner.

An internally threaded sleeve 41 extends centrally through the valve 31 projecting both above and below said valve, being fixed to said valve and preferably made integral 110 therewith. One end of said sleeve is positioned in the sleeve 28 within the casing and and into which extends the rod 26 which is in operative engagement with the bell crank lever arm 23'. The upper end of the sleeve 115 41 extends through the central opening 36 in the casing closure 34 and through the boss 37 thereof. A hand wheel 42 has a shank 43 externally threaded to engage the interior thread of the sleeve 41, said shank 120 being of greater length than said sleeve to adapt it to abut the upper end of rod 26.

What may be termed a self-packing washer is engaged with the sleeve 41 on the lower face of the closure 34 and which is 125 composed of a leather washer 44 about one-sixteenth of an inch more or less, which is forced into position by a brass washer 45 disposed below said washer 44 and which is preferably of the same thickness as the 130

washer 44 and has a projection 46 on its upper face around the opening therein so that when the washers are forced toward the closure 34 the leather washer is caused to 5 enter the aperture 36 and forms an effective packing. The washer is held in position by a spiral spring 47 coiled around the sleeve 41 and which bears at one end against the washer 45 and at its other end against the 10 valve 31 and operates to hold the washer in position and to force the valve downwardly into engagement with its seat, thus performing a double function and preventing any lost motion.

15 From the above description, it will be obvious that when the water flowing through the casing 13 is cold, the tube 17 will contract and thereby forcibly eject the rod 24, causing it to move forward into engagement 20 with the arm 23 of the bell crank 22 and this movement of said lever causes its other arm 23' to move upwardly and thereby raise the rod 26 and the shank 43 resting thereon, thus raising sleeve 41 and opening the valve 31 25 and permitting the gas to flow freely to the burner 11 where it is ignited by the pilot and the flame from which quickly heats the water in the coil 5 causing it to circulate and pass upward into the boiler 1 through 30 the connections above described and also out through the pipe 9 to a radiator if the device be used in connection with such. When the water reaches a predetermined temperature, the heat thereof will cause the tube 17 to expand and permit the rod 24 under the 35 weight of the lever 22 and the parts bearing thereon to move inwardly into the tube 17, thus causing the lever arm 23' to drop and the valve 31 to seat under the action of the 40 spring 47, thereby cutting off the gas supply to the burner 11 and preventing the water from overheating.

It will thus be seen that this heater is 45 entirely automatic and is controlled by the temperature of the water which flows 50 through the thermostat casing 13. When the water gets cold, the thermostat operates to open the valve for supplying fuel to the burner and when it reaches a predetermined 55 heat, it operates to permit the closing of the valve under the action of its spring 47 and cut off the fuel supply, thereby economizing greatly in fuel and at the same time keeping the water within the system at a predetermined temperature.

The valve may be set to open at any desired temperature of the water by varying the distance between the end of the expansion tube 17 and valve, which is accomplished by turning the hand wheel 42 in the direction indicated by the arrow *a* in Fig. 5, the adjusting screw 43 carried by said wheel being a right hand threaded screw; therefore when the wheel is turned in the 60 direction of arrow *a*, the distance between

the end of the tube 17 and the lower end of spindle 43 is increased and when it is turned in the direction of arrow *b*, it is correspondingly decreased. This varying of the distance between the lower end of spindle 43 70 and the open end of the expansion tube provides for the opening of valve 31 according to the temperature of the water, and which is controlled by the adjustment of spindle 43 relative to rod 26. 75

It will be understood that when the spindle 43 is raised it will be necessary that rod 26 be lifted a greater distance before the upper end thereof abuts the spindle and operates to open the valve, and consequently 80 rod 24 must be correspondingly projected in order to so raise rod 26. The projection of rod 24 is controlled by the contraction of tube 17 which occurs on the lowering of the temperature of the surrounding water and 85 hence the temperature of the water must be lower when spindle 43 is raised before the opening of the valve will take place, and vice versa. When spindle 43 is lowered the rod 24 will operate to open the valve on a 90 slight drop in temperature of the water.

In the operation of this apparatus, cold water is admitted through the opening 15' in the coupling 15 until the system becomes filled and when the gas is lighted at the 95 burner 11, the water in coil 5 is quickly heated and circulation through the system started, the water passing from the coil 5 in the boiler 1 through the pipe 4 and into the radiators through pipe 9 and returns to casing 100 15 through opening 15'. The water from the boiler pipe 3 enters the coupling 15 and passes through the casing 13 into the lower end of the coil 5 connected with the coupling 14, the water thus flowing over the 105 thermostatic tube 17 which controls the flow of fuel to the burner.

If water is drawn from the boiler 1 through the outlet 2, cold water from the lower end of the boiler flows over the thermostatic tube through the casing 13, thereby causing said tube to contract and the flow of fuel to be instantly turned on, thus rendering the device instantaneous, the turning on and cutting off of the fuel being dependent 110 upon the temperature of the water which flows over the thermostatic tube. This apparatus has no mixer, consequently there can be no flash-back, thus avoiding danger 115 of explosion. 120

The coil 5 of this apparatus will not scale or lime up, owing to the fact that cold water is admitted to the coil, causing it to contract and expand quickly, thus breaking up all deposits and preventing scaling. 125

I claim:

In a thermal valve, a casing having an apertured partition, supply and outlet means at opposite sides of said partition, a tubular guide on one end of the casing 130

4
in line with the aperture of said partition and a stuffing box on the other end of said casing in line with said guide, said guide extending into said casing and having an apertured lateral lug on its inner end, a valve for the aperture of said partition having a tubular hub received slidably in the inner end of said tubular guide, the opposite end of said hub being slidably received in said stuffing box, a thermally operated plunger slidable in the outer end of said guide, a screw threaded through said tubular hub and bearing against said plunger to adjust

the movement of the valve, and a finger extending from said valve parallel with said 15 tubular hub and received slidably in the aperture of said apertured lug, whereby to prevent rotation of said valve and hub when said screw is adjusted.

In testimony whereof I have hereunto 20 set my hand in the presence of two subscribing witnesses.

HERBERT PAYNE FISHER.
